UNITED STATES PATENT OFFICE.

ALFRED E. BUHRKE, OF RIVER FOREST, ILLINOIS, ASSIGNOR TO R. H. BUHRKE CO.,
OF CHICAGO, ILLINOIS, A CORPORATION OF ILLINOIS.

GOLF-CLUB CONSTRUCTION.

Application filed December 9, 1927. Serial No. 238,748.

This invention relates to golf club construction and has special reference to the seating or anchoring of the striking face and the impact plugs in the golf club head.

5 In order to afford a maximum rigidity at the point of impact between the golf club head and the ball, the golf club head is provided with a striking face of a different material than that of the head. A golf club 10 head is ordinarily made of wood and, it has been found very desirable to use a fiber, ebony and other characteristically hard materials for affording the solidity necessary to enable the golfer to get great distance to the 15 flight of the ball and to prevent the club from rebounding and thereby enabling the golfer to "follow through" with the stroke to give the proper direction to the ball.

Inasmuch as the striking face receives the 20 impact of the blow, there is a tendency for the same to become loosened within the club head which materially affects the solidity of the blow. Further, the aforementioned tendency of the face plate to become loosened 25 causes the vibrations set up in the golf club head to become deadened to a considerable extent which likewise materially affects the flight of the ball.

By means of the present invention, the 30 aforementioned objectionable features and difficulties are overcome by providing a striking face of such a shape as to securely anchor the same in the golf club head.

Other advantages will hereinafter be more 35 fully described and for a better understanding of the nature, scope and characteristics of this invention, reference may be had to the accompanying drawing in which drawing:

40 Figure 1 is a front elevational view of a golf club head showing the novel form of striking face as embodied in this invention;

Fig. 2 is a bottom plan view of Fig. 1; and

45 Fig. 3 is a side elevational view of Fig. 1 showing a portion thereof in section as indicated by the line 3—3 of Fig. 1.

Referring now to the drawing, a golf club head 10 is shown which is preferably formed of wood, although any suitable material may 50 be used. A striking face 11 is seated or anchored in the golf club head to form a solid impact member and is preferably formed of fiber, hard rubber or other suitable hard material. The striking face is substantially

X-shaped having its upper and lower ends 55 extending flush with the upper and lower surfaces of the golf club head. The remaining two edges converge inwardly from the upper and lower edges and meet substantially centrally of the face.

A plurality of impact inserts 12 are inserted in apertures formed in the striking face 11 and extend into the golf club head 10. In this particular instance, four such inserts are employed and are preferably formed of fiber, ivory or other hard material for affording a desirable striking surface. These impact inserts are secured in position in the golf club head by means of main insert 13 centrally disposed relative to the previously 70 described inserts. The insert 13 comprises a main body portion extending through the striking face a substantial distance into the golf club head. The body portion is provided with a head which is countersunk in 75 the striking face 11. The periphery of the head of the insert 13 is arranged to overlap the periphery of the inserts 12, the inserts being notched so as to provide a seat for the overlapping portion. A screw 14 is inserted 80 in the bottom of the golf club head and extends to engage the body portion of the insert 13. Inasmuch as the insert 13 engages and firmly holds the inserts 12 in position in the golf club head, the screw 14 is indirectly 85 the securing means for the entire group of inserts.

The bottom surface of the golf club head is provided with a sole plate 15 which is secured thereto preferably by means of screws 90 16. The sole plate is formed substantially of a mushroom shape having a stem portion 17 extending rearwardly from a head portion 18. Inasmuch as the sole plate receives a considerable portion of the shock attendant 95 with the force of the blow, as for example, when the blow is "topped" there is a tendency for the sole plate to become loosened, and therefore, the internal edges of the stem portion 17 converge forwardly of the golf club 100 head from the rear end thereof.

It will be noted that the force of impact will be received upon the shoulders of the head portion and if the impact is off center relative to a central axis through the sole plate, the direction of the lines of force will extend laterally across the head of the golf club head to distribute the vibrations there-

through. It would be improbable that the center of the golf ball and the center of the golf club head and sole plate would coincide, and therefore, it would be usual that these 5 vibrations would be set up in the club. The screws 16 have no function therefore other than to prevent the sole plate from falling off the bottom of the club as they do not receive the force of impact. Again, the screw 10 14 does not receive the force of impact as it is covered and substantially inlaid in the golf club head and is prevented from becoming loosened by means of the sole plate. The main impact insert 13 being held in position 15 by the screw 14 will therefore not be able to become loosened, whereby the auxiliary impact inserts 12 are firmly held in position.

The striking face 11 is held in a substantially integral relation with the golf club 20 head by means of the inserts. However, the striking face of all golf clubs are slightly tapered to give the necessary height or rise to the ball. By so doing, the force of impact tends to displace the striking face vertically 25 of the golf club head. Although it is usual to provide the striking face of a frusto-conical shape thereby permitting of a wedging action, it is believed that the present invention teaching the use of a substantially 30 X-shaped striking face to obtain a wedging action in both directions is novel and provides for a firm rigid position of the striking face in the club head which will not loosen under severe usage.

35 While but a single embodiment of this invention is herein shown and described, it is to be understood that various modifications may be apparent to those skilled in the art without departing from the spirit and scope 40 of this invention, and therefore, the same is

to be limited only by the scope of the prior art and the appended claims.

I claim:

1. The combination with the head of a golf club, of a striking face inlaid therein, said 45 striking face comprising oppositely converging portions, an insert comprising an enlarged head portion and a smooth body portion, said head portion being seated in said face and having the outer surface thereof set 50 flush with the outer surface of said striking plate, and means for engaging said insert for holding said face plate and said insert in a fixed relation with said club head.

2. The combination with the head of a golf 55 club, of a striking face inlaid therein, said striking face comprising oppositely converging portions, an insert comprising a head portion and a body portion, said head portion being seated in said face and having the 60 outer surface thereof set flush with the outer surface of said striking plate, means for engaging said insert for holding said face plate and said insert in a fixed relation with said club head, and means for locking said 65 engaging means.

3. The combination with the head of a golf club, of a striking face inlaid therein, said striking face comprising an X-shaped member for preventing an upward or downward 70 displacement, an insert extending through said striking face and terminating in said head, the outer surface of said insert being set flush with the outer surface of said face, a pin for engaging said insert, and a plate 75 on the bottom of said club head for locking said pin.

In witness whereof, I have hereunto subscribed my name.

ALFRED E. BUHRKE.
